EXTRUSION NOZZLE

William J. McCue, Chicago, Ill., assignor to Industrial Patents Corporation, Chicago, Ill., a corporation of Delaware

Application December 13, 1935, Serial No. 54,199

15 Claims. (Cl. 226—93)

This invention relates to an improved method and apparatus for extruding a meat product.

One of the objects of this invention is to provide an improved means for filling trays with a comminuted plastic meat product devoid of air pockets.

Another object of this invention is to provide an improved extrusion nozzle in which a comminuted meat product under pressure is forced through an elevated, graduated passageway in a manner preventing the formation of air pockets therein.

Another object of this invention is to provide a novel method of introducing a comminuted product into a receiving tray devoid of air pockets by forcing the product under pressure through an elevated passageway to cause a back pressure, said passageway being graduated to an opening substantially the width of the receiving tray.

Other objects will be apparent from the description and claims which follow.

I have found that meat loaves formed from a comminuted product contain, to a large degree, a number of air pockets of varying sizes. Such air pockets have a deleterious effect upon the finished product, prevent a maximum weight in a minimum sized loaf and cause an unsightly appearance in the sliced product. By use of my present method and apparatus, I am able to provide maximum efficiency in the formation of meat loaves free of air pockets.

Referring to the drawing:

Figure 1 is a perspective view illustrating the device of the present invention secured to one type of filling machine with which it may be utilized and a stationary support for resting the receiving tray.

Figure 2 is an enlarged side elevational view illustrating the device of the present invention with the receiving tray shown in dotted lines.

Figure 3 is a plan view of Figure 2.

Figure 4 is a plan view of the flange member at the extrusion end of the device.

While any of the conventional types of extruding machines may be utilized with the present invention, I have illustrated in Figure 1 of the drawing one of the simpler types, in which the numeral 1 represents a tank having a cover 2 made air-tight by yoke 3 and press screw 4. Material in tank 1 is forced under pressure through outlet line 5 through the medium of a piston or other suitable means provided within tank 1. The piston in tank 1 may be operated by compressed air entering through line 6, controlled by a suitable valve operated from lever 7.

The extrusion of material from tank 1 is controlled by cock 8 in line 5.

My improved extrusion nozzle may be formed from sheet metal or other suitable material and comprises a cylindrical collar portion 9 provided at one end with radial flange 10 and at its opposite end with an upwardly extending, outwardly flared passageway 11. In practice, passageway 11 is elevated substantially 39° and in the course of its elevation assumes the shape of a substantial rectangle gradually increasing in width and decreasing in height.

At a suitable point in elevation, passageway 11 makes a sharp curve downwardly to open end 12 for suitably dispensing the product. The side walls of downward portion 13 are parallel throughout their length and preferably define an opening of common relationship to passageway 11 at its highest point in elevation. Flange member 14 is welded or otherwise secured at open end 12 at right angle to downward portion 13.

Collar nut 15 having wing members 16 is provided on collar 9 for securing the device by means of flange 10 to line 5 of tank 1.

In practicing the present invention, receiving tray 17 of the conventional type may be manually held about flange 14 as shown in Figure 2 of the drawing or, if desired, may be supported upon a compressible supporting means not shown. Comminuted material is forced under pressure from tank 1 to enter passageway 11. Due to the inclination of passageway 11, a back pressure will result in the material passing therethrough and cause the material to compact in a manner devoid of air pockets. This back pressure, assisted by the decreasing height of passageway 11, will also cause the material to spread evenly with the increasing width of passageway 11.

Flange 14 is in operative relationship with tray 17 and serves to prevent the product extruded from opening 12 from rolling or folding over during the filling of tray 17, by which the product is continuously compacted free of air pockets throughout the filling operation. As the stuffing operation proceeds, tray 17 is commensurately lowered with its filling until the material is level with the top of the tray, whence the supply is cut off by cock 8. The filled tray is then pressed firmly against the under side of flange 14 and removed by sliding it sideways, thereby providing a smooth surface on the top of the loaf.

It will be understood that while the device of the present invention has been described for use in forming a product of comminuted material,

such device is equally adapted for use with plastic and semi-liquid materials.

I claim:

1. In a device of the class described, an extrusion nozzle defining a substantially rectangular upwardly inclined passageway having a gradually increasing dimension in one direction in cross section and a gradually decreasing dimension in the other direction in cross section for preventing the formation of air pockets in a plastic product passed therethrough under pressure, said passageway being terminated in a downwardly extending outlet portion. 5
2. In a device of the class described, an extrusion nozzle defining a substantially rectangular passageway inclined upwardly approximately 39 degrees, having a gradually increasing dimension in one direction in cross section and a gradually decreasing dimension in the other direction 10 in cross section for preventing the formation of air pockets in a plastic product passed therethrough under pressure, said passageway being terminated in a substantially rectangular, downwardly extending, outlet portion at its elevated end. 15
3. In a device of the class described, an extrusion nozzle defining a substantially rectangular upwardly inclined passageway having a gradually increasing dimension in one direction in cross-section and a gradually decreasing dimension in the other direction in cross section for preventing the formation of air pockets in a plastic product passed therethrough under pressure, said passageway being terminated in a downwardly extending discharge portion and an outwardly extending flange member secured at the outlet end of said discharge portion in operative association with a product receiving tray to compact the material deposited therein. 20
4. In a device of the class described, an extrusion nozzle defining a substantially rectangular passageway inclined upwardly approximately 39 degrees, having a gradually increasing dimension in one direction in cross section and a gradually decreasing dimension in the other direction in cross section for preventing the formation of air pockets in a plastic product passed therethrough under pressure and terminating in a substantially rectangular downwardly extending discharge portion, and an outwardly extending flange member secured at the outlet end of said discharge portion in operative association with a product receiving tray to compact the material deposited therein. 25
5. An extrusion nozzle of the class described defining an upwardly inclined passageway having a gradually increasing dimension in one direction in cross section and a gradually decreasing dimension in the other direction in cross section and provided with a substantially rectangular outlet at its elevated end for preventing the formation of air pockets in a plastic product passed therethrough under pressure. 30
6. An extrusion nozzle of the class described defining an upwardly inclined passageway having a gradually increasing dimension in one direction in cross section and a gradually decreasing dimension in the other direction in cross section and terminating in a substantially rectangular, downwardly extending, discharge portion at its elevated end and an outwardly extending flange member secured at the outlet end of said discharge portion. 35
7. An extrusion nozzle of the class described defining a passageway inclined upwardly approxi- 40
8. In a device of the class described, an extrusion nozzle defining an upwardly inclined passageway for preventing the formation of air pockets in a plastic product passed therethrough under pressure, said passageway being outwardly flared in cross section in a sidewise direction. 45
9. In a device of the class described, an extrusion nozzle defining an upwardly inclined passageway for preventing the formation of air pockets in a plastic product passed therethrough under pressure, said passageway being outwardly flared in cross section in a sidewise direction and terminating in a downwardly extending outlet portion. 50
10. In a device of the class described, an extrusion nozzle defining an upwardly inclined passageway for preventing the formation of air pockets in a plastic product passed therethrough under pressure, said passageway being outwardly flared in cross section in a sidewise direction and terminating in a downwardly extending outlet portion and an outwardly extending flanged member secured to the outlet end of said discharge portion. 55
11. In a device of the class described, an extrusion nozzle defining an upwardly inclined passageway for preventing the formation of air pockets in a plastic product passed therethrough under pressure, said passageway at its lowermost end being substantially circular in cross section and outwardly flared in a sidewise direction to a form substantially rectangular in cross section at its uppermost end. 60
12. In a device of the class described, an extrusion nozzle defining an upwardly inclined passageway for preventing the formation of air pockets in a plastic product passed therethrough under pressure, said passageway at its lowermost end being substantially circular in cross section and outwardly flared in a sidewise direction to a form substantially rectangular in cross section at its uppermost end, said passageway being terminated in a downwardly extending outlet portion. 65
13. In an extrusion device adapted for the discharge of plastic product into a receiving tray, means preventing the formation of air pockets in the discharged product comprising a downwardly extended substantially rectangular nozzle having one dimension substantially equal to one dimension of the receiving tray and a compressing and compacting means communicating with the nozzle comprising an upwardly inclined passageway outwardly flared in a sidewise direction in cross section approaching the nozzle. 70
14. In an extrusion device adapted for the discharge of plastic product into a receiving tray, means preventing the formation of air pockets in the discharged product comprising a downwardly extended substantially rectangular nozzle having one dimension substantially equal to one dimension of the receiving tray and a compressing and compacting means communicating with the nozzle comprising an upwardly inclined passageway having a gradually increasing dimension in one direction in cross section and a gradually de- 75

creasing dimension in the other direction in cross section approaching the nozzle.

15. In an extrusion device adapted for the discharge of plastic product into a receiving tray, means preventing the formation of air pockets in the discharged product comprising a downwardly extended substantially rectangular nozzle having one dimension substantially equal to one dimension of the receiving tray and a compressing and

compacting means communicating with the nozzle comprising an upwardly inclined passageway having a gradually increasing dimension in one direction in cross section and a gradually decreasing dimension in the other direction in cross section approaching the nozzle, the nozzle at its discharge end being provided with an outwardly extended flange member. 5
